UNITED STATES PATENT OFFICE.

ALBERT H. STEBBINS, OF LOS ANGELES, CALIFORNIA.

OPERATING MEANS.

Application filed December 20, 1924. Serial No. 757,173.

This invention relates to means for imparting a vibratory movement to concentrator decks, screens and other vibratory frames, and more particularly to means for imparting a progressive movement to the same.

A progressive type of vibratory movement is commonly employed to advance materials along the material supporting surface of a deck or screen, and may be employed for other purposes. The supporting frame which receives the progressive movement is usually relatively heavy and the operating parts are subject to a severe strain each time the movement of the frame is suddenly checked to advance the materials along the frame. As a result, the operating mechanism is usually subjected to severe wear and difficulty has been experienced heretofore in securing a simple and durable form of operating means that will produce the desired progressive movement.

The present invention therefore relates to a strong and durable form of operating means for producing a progressive movement and which is extremely simple in construction.

In carrying out the present invention an operating lever is employed which is connected to the frame to be vibrated, and a cam is provided to rock the lever so that it will pull the frame in one direction and then releases the lever to allow the frame to move rapidly in the opposite direction under the action of compressed springs or other yielding means.

One feature of the present invention resides in a roller or antifriction device interposed between the lever and cam to eliminate friction between these elements. Another feature of the invention resides in the construction of the lever and the connections for imparting movement from the lever to the frame that is vibrated.

Other features of the invention in addition to the above will be hereinafter described in connection with the accompanying drawings illustrating good, practical forms of the invention.

In the drawings:—

Fig. 1 is a side elevation of a machine employing the operating means of the present invention.

Fig. 2 is a sectional view taken on line 2—2 of Fig. 1.

Fig. 3 is a side view of means for supporting the frame for back and forth movement; and

Fig. 4 shows a different type of cam for operating the rocking lever.

The operating means of the present invention may be used for various purposes, and in the construction shown, a frame 10 is mounted for back and forth movement on a supporting base constructed of longitudinally extending beams 11 supported in spaced relation by uprights 12 and the sides of the base are connected by transversely extending braces 13.

The frame 10 may constitute a screen 70 having the usual screening surface, a concentrator deck, or other device employing a vibratory movement. The means for supporting the frame 10 for back and forth movement may be variously constructed, and 75 is shown as consisting of transversely extending shafts 14 supported near the ends of the base by brackets 15. The opposite ends of the shaft 14 are provided with downwardly extending arms 16 having the stub shafts 17 extending therefrom near their lower ends. The stub shafts 17 are journaled in bearing blocks 18 secured to the frame 10. As the arms 16 swing back and forth they impart a slight upthrust movement to the frame 10, which is desirable.

In the construction shown, the frame 10 is urged in the right-hand direction by one or more coiled springs 19, one end of which is seated in a cup 20 secured to the frame 10, 90 and the other end is seated in a cup 21 that is adjustably supported by the threaded bolt 22 extending through the lug 23 secured to the supporting base.

The means for positively moving the frame 10 in the opposite direction consists of a lever 24 supported for rocking movement by the transversely extending shaft 25 the ends of which are supported by bearings 26. The lever 24 has an enlarged head 27 that encircles the shaft 25 and in this head are formed the cable-receiving grooves 28. The connection between the lever 24 and frame 10 comprises a cable 29, an intermediate portion of which is looped about 100 the lever at 30 and the two cable strands thus formed extend around the head 27 within the grooves 28, and the ends of these strands are fastened to a block 31 secured by threads or other means to the bolt 32. 110

The bolt 32 extends through the spaced brackets 33 fastened to the frame 10 and this bolt may be adjusted in the direction of its length to tension the cable by operating the nuts 34.

A cam 35, secured to and rotated by the shaft 36 is provided to rock the lever 24 in a direction to pull the frame 10 in a left hand direction. The shaft 36 is journaled in bearings 37 and may be driven by a pulley 38. The configuration of the cam 35 may be varied as desired to impart different movements to the frame 10, and the lever 24 is provided with a roller 39 against which the cam 35 rotates. In this manner friction between the lever and cam is eliminated. The outer end of the lever 24 may be forked to receive the roller 39 between the forked arms and the roller is mounted upon a pin 40 secured to the forked arm. If the cam and roller are both formed of metal, it may be desirable to reduce the shock and noise produced by one striking the other and this may be accomplished by providing the roller with a tire 41 formed of rubber or other yielding material.

The cam shown in Figs. 1 and 2 is provided with two diametrically disposed projections 42, and as the cam rotates in the direction indicated by the arrow the lever is gradually forced upwardly to pull the frame 10 in a left-hand direction and is then suddenly released and forced in the opposite direction by the compressed springs 19 as the projection 42 moves out of engagement with the roller 39. This permits the frame 10 to move rapidly in a right-hand direction until it is suddenly stopped by the roller 39 striking against the reduced diameter of the cam. Each time the movement of the frame is suddenly stopped the materials being treated slide lengthwise of the frame a slight distance in the desired progressive manner.

The cam 35 is constructed to impart a substantial progressive movement to the frame

10, while the differently shaped cam 43 of Fig. 4 will impart a much smoother movement to the device it operates. The arrangement of the cable shown provides a strong, durable connection between the lever and frame, and the construction of the various parts described is such that they will not be readily injured by the dirt and dust that usually accompany the operation of screens and concentrators.

What is claimed is:

1. In a device of the class described, a supporting base, a frame supported by the base for back and forth movement, resilient means for urging the frame in one direction, and mechanism for forcing the frame in the opposite direction, comprising a pivoted lever having an enlarged head surrounding the lever pivot, a cable having an intermediate portion looped about the lever and having the pair of strands formed by the loop extending in the same direction about the head to the frame to which they are anchored, a roller at the outer end of the lever, and a rotating cam acting against said roller to rock the lever.

2. In a device of the class described, a supporting base, a frame supported by the base for back and forth movement, yielding means for urging the frame in one direction, and mechanism for moving the frame in the opposite direction, comprising a pivoted lever having a head surrounding the lever pivot, a cable having an intermediate portion looped about the lever and having the pair of strands formed by the loop extending in the same direction about said head to the frame to which they are anchored, a roller mounted upon said lever and provided with a resilient tire, and a rotating cam acting against said roller to rock the lever.

In testimony whereof, I have signed my name to this specification.

ALBERT H. STEBBINS.
